UNITED STATES PATENT OFFICE.

WILLIAM H. LEWIS, OF BROOKLYN, ASSIGNOR TO E. & H. T. ANTHONY & COMPANY, OF NEW YORK, N. Y.

FILM-SUPPORTING FRAME FOR PHOTO-CAMERAS.

SPECIFICATION forming part of Letters Patent No. 402,680, dated May 7, 1889.

Application filed December 13, 1888. Serial No. 293,492. (No model.)

To all whom it may concern:

Be it known that I, WILLIAM H. LEWIS, a citizen of the United States, and a resident of Brooklyn, in the county of Kings and State of New York, have invented certain new and useful Improvements in Film - Supporting Frames for Photographic Cameras, of which the following is a specification.

My invention relates to an improved device whereby sensitized photographic "films" or "sheets," so called, may be used in plate-holders intended for use with glass "dry-plates," so called, and in the same manner as dry-plates are now used, whereby those now owning cameras provided with plate-holders intended for use with dry-plates may, without change therein, use photographic films interchangeably with the dry-plates; and my invention in its most approved form is so constructed that the sensitive surface of the film will be as accurately located relative to the focus of the lens as is the sensitive surface of the dry-plate.

The invention consists in the construction of the film holding and supporting frame, hereinafter set forth, and in its combination with a sensitive film, substantially as claimed.

In the drawings the same reference-letters indicate the same parts in all the figures.

Figure 1 illustrates a side plan view of a plate-holder, the film being in position and the slide withdrawn. Fig. 2 illustrates a vertical sectional view on the line $x-x$ of Fig. 1. Fig. 3 illustrates a horizontal view on the lines $y-y$ of Fig. 1. Fig. 4 illustrates an enlarged sectional view the same as Fig. 2. Fig. 5 illustrates a perspective view of the film in position on the supporting-plate separated from the plate-holder. Fig. 6 illustrates a plan of a plate-holder, the film-supporting plate being so constructed and arranged that the film is presented to the lens in position to take a horizontal picture instead of a vertical one, as shown in Fig. 1.

A is the plate-holder. It is or may be constructed in all respects as now usual—that is to say, it has the end bars, B, the side bars, C, which are provided with rabbets or ledges C', (best seen in Fig. 4,) against which the sensitive surface of the dry-plates or the surface of the film, as the case may be, rests. It also has the slides D D', and if it be a double

plate-holder, as shown, it has the usual central diaphragm, E, provided with springs F, for pressing the sensitive surface against the ledges C'. (Best seen in Fig. 5.)

G is the film-supporting frame, which is the special subject of this invention. It consists of a plate or piece of material, H, which is of the same size as the dry-plate intended to be used in the plate-holder, whatever that size may be. I prefer to make it of a hard tough quality of pasteboard or straw-board of sufficient thickness to be quite stiff and not easily bent. It may, however, be made of wood, metal, or other preferred material. This plate is provided at each end with flanges II, which are attached to the end of the plate in any preferred manner and overlap it, extending inwardly, and are separated from the surface of the plate by a distance sufficient to allow the easy insertion under them of the sensitized film. I show the flanges as made of metal, suitably bent into proper form and having tangs i i, &c., which pierce the plate G and are riveted on the upper side thereof. This is one method only, however, of making and securing the flanges. They may be made of such material as desired and attached to the plate, or made of the same piece with the plate and in any desired manner. I prefer that the ends of these flanges (shown at h h, Fig. 5) should not extend quite to the edges of the plate, but should be cut off at such distance therefrom as that the ends of the flanges will not touch the ledges C' C' on the plate-holder. Thus they will not interfere with the accuracy of focus of the sensitized film, because the sensitive surface of the film will then rest immediately upon the ledges C' C' exactly as the sensitized surface on the dry plate does when it is used. J is the sensitized film. It may be made in any desired manner and of any preferred material, including both the sensitizing material as well as the supporting sheet or fabric; but I have found that the now well-known celluloid sheet, coated with gelatino-argentie emulsion, acts very successfully in connection with my device. Paper or other fabric may, however, be used, as stated. This sensitized film is cut of such size that it substantially coincides with the dimensions of the plate H, and consequently when in po-

sition on that plate, with its ends under the flanges II, they will hold it down endwise, and the edges of the film, (seen at K K,) projecting laterally beyond the ends of the flanges, come 5 in contact with the ledges C' C' on the plate-holder, and, being firmly pressed against said ledges by the operation of the springs F F, they are flattened out into intimate contact with the plate G, and thus the whole surface 10 of the sensitized film is made to rest snugly against the surface of the plate H, and is therefore brought into proper focal position.

It will be observed that in the use of my frame I avail myself of a physical law that 15 governs all fabrics of the classes under contemplation—*i. e.*, that they all warp or curl in the direction or toward the surface upon which the sensitizing material is applied. Thus the resiliency of the sheet or film compels it to 20 hug close upon and conform to the surface of the supporting-plate.

From the foregoing it will be seen that by 25 my invention sensitized sheets made of such fabric as preferred, now ordinarily called “photographic films,” may be used interchangeably with dry-plates in plate-holders intended for use with dry-plates only and that no change whatever is needed in the plate-holders; also, that the same film-supporting 30 frame, G, may be reused indefinitely, and also that by putting the flanges on the long sides

of the plate H, instead of on the shorter sides or ends, as seen in Fig. 6, the films may be used for taking horizontal pictures, thus there being a considerable saving effected in the 35 amount of film required, because only so much is used as is required for the picture, there being no necessity for endwise extension of the film for the purposes of support or to stretch it, as is necessary under the methods 40 now employed for the use of such films.

My film-supporting frames are exceedingly inexpensive, and, being light in weight and non-fragile, are manifestly superior to the glass dry-plates now in use. 45

Having described my invention, I claim—

As a new article of manufacture, a frame for a sensitized photographic film or sheet comprising a supporting-plate having flanges at opposite sides thereof, the ends of which 50 fall short of the edges of the supporting-plate by a distance sufficient to clear the plate-supporting ledges of the plate-holder, substantially as set forth.

Signed at New York, in the county of New 55 York and State of New York, this 11th day of December, A. D. 1888.

WILLIAM H. LEWIS.
